RUNNING SAND TOOTH TIMER

Edward K. Beckwith, 303 La Marina,
Santa Barbara, Calif. 93109

Filed Aug. 2, 1974, Ser. No. 494,195

Term of patent 14 years

Int. Cl. D10—03

U.S. Cl. D10—44

FIG. 1

FIG. 2

FIG. 3

FIG. 4

FIG. 5

FIG. 1 is a front perspective view of a running sand tooth timer showing my new design;

FIG. 2 is a top plan view thereof;

FIG. 3 is a bottom plan view thereof;

FIG. 4 is a rear elevational view thereof; and

FIG. 5 is a left side elevational view thereof.

I claim:

The ornamental design for a running sand tooth timer, as shown.
